UNITED STATES PATENT OFFICE

WILLIAM DUBILIER, OF NEW ROCHELLE, NEW YORK, ASSIGNOR TO DUBILIER CONDENSER CORPORATION, A CORPORATION OF DELAWARE

ELECTRICAL STRUCTURE

Application filed February 12, 1924, Serial No. 692,328. Renewed March 28, 1930.

My invention relates to electrical structures and particularly to racks or standards for supporting electrical condensers.

One object of my invention is to provide a structure of the above indicated character that shall be free of damaging stresses caused by the electrostatic field between spaced conducting sections thereof.

Another object of my invention is to provide an electrical structure that shall comprise alternate insulating and conducting sections, in which electrostatic stresses are prevented from adversely affecting the insulating sections.

15 Another object of my invention is to provide a supporting column for high-potential electrical devices in which ultimate arc-over is confined to a definite local path between adjacent spaced conducting sections thereof.

20 Another object of my invention is to provide a supporting standard that shall comprise enclosed electrostatic-stress-assuming or safety-arc-gap members between adjacent sections thereof.

25 Another object of my invention is to provide a high potential condenser-supporting rack, in which the electric field shall be so controlled as to materially increase the voltages at which the device may operate.

30 Another object of my invention is to provide a multi-section, high-voltage condenser structure that shall be less dangerous to operators and to surrounding objects.

Another object of my invention is to provide a protected condenser structure that shall be simple and durable in construction, economical to manufacture and effective in its operation.

With such objects in view, as well as other advantages which may be incident to the utilization of the improvement, the invention consists in the parts and combinations thereof hereinafter set forth and claimed, with the understanding that the several necessary elements constituting the same may be varied in proportion and arrangement without departing from the nature and scope of the invention.

My Patent No. 1,628,627, issued May 10, 1927, sets forth an electrical structure, simi-

lar to the one herein described, to which reference may be had for a better understanding of my present invention.

The device of the copending application comprises a rack or standard that is built-up of alternate insulating and conducting sections, on the latter of which high-potential condensers are supported. The construction and relation of parts are such as to permit condensers of a great variety of voltages to be economically constructed from a relatively small variety of stock parts, and while these parts are set up in the assembled device to uniformly distribute the electric field between the sections and to, thereby, reduce the likelihood of flashover, ultimate breakdown, caused by excessive voltage conditions, may occur over the exterior of the structure. Such a condition, which may be caused by lightning discharges in the condenser circuit, by interference with the other circuits and by other causes, is a condition from which no electrical apparatus is immune, unless adequate protecting means is provided, and is likely to not only damage or destroy the condenser but to extend these effects to surrounding objects and persons.

It is my aim to so completely protect an electrical structure, for wireless telegraph and other service similar to the device of my copending application, as to substantially eliminate the possibility of exterior surface discharges, thereby, precluding the damaging effects above referred to, and rendering the device more effective in operation and increasing the operating voltages to values

above those by which a structure of corresponding size, not embodying my invention, may be operated. My invention also provides a high-tension, high-frequency structure having low electrical losses.

In practicing my invention, I provide an electrical structure comprising alternate insulating and conducting sections, between the latter of which inclosed co-operating electrostatic-stress-assuming members are so constructed and positioned as to confine ultimate breakdown discharges to a definite local path that conducts the discharges to ground before damage occurs. The stress-

assuming members are also so related and ruggedly constructed as to assume extremely violent discharges without material injury from the charring, fracturing and distorting effects of such discharges.

In order to make the invention more clearly understood, means are shown in the accompanying drawings for carrying the same into practical effect without limiting the improvements in their useful applications to the particular constructions which, for the purpose of explanation, are made the subject of illustration.

Figure 1 of the accompanying drawings, is an outline plan view of an electrical structure or condenser rack embodying my invention.

Fig. 2 is a side-elevational view of the structure shown in Fig. 1,

Fig. 3 is an enlarged sectional side view of a portion of the device, as shown in Fig. 2,

Fig. 4 is a detail view, taken along the line IV-IV of Fig. 1 and at right angles to a portion of the device shown in Fig. 3, to the same scale as Fig. 3, and

Fig. 5 is a view similar to Fig. 3 showing a modified form of my invention.

Referring to Figs. 1, 2, 3 and 4, an electrical structure, for which my invention is particularly adapted, comprises, in general, a base member 1, a plurality of alternately superposed insulating and conducting sections 2 and 3, respectively, and a plurality of condensers 4, several of which are mounted on each of the conducting sections 3.

The insulating sections 2 are preferably built up to form a single central vertical column, between which the conducting sections 3 are mounted and from which the sections 3 extend laterally or radially.

The sections 2 preferably comprise hollow cylindrical insulating members, such as porcelain, wood or other material having exterior surface-creepage corrugations 5.

Each conducting section 3 preferably comprises complementary half-portions 6 having apertured flanges 7 for the reception of bolts 8 by which the portions 6 are clamped together and in position against the ends of adjacent insulating sections 2. Clamping portions 9 on the portions 6, as shown in Figs. 3 and 4, so engage the end corrugations 5 of the adjacent insulating sections 2 as to permit the half portions 6 to not only radially clamp the insulating sections 2, with respect to the longitudinal axis thereof, but to effect a clamping action tending to draw the insulating sections 2 longitudinally together. This construction mounts the conducting sections 3 securely in position and binds the insulator sections firmly together to constitute a composite rugged column. Flexible yielding cushioning material 15, such as felt or fiber, is placed between the ends of the insulating sections 2 and the complementary

half portions 6 to assist in clamping the parts together and to prevent damage by unequal expansion and contraction of the metal and insulating parts.

A semi-discoidal web portion 10, having a semi-cylindrical recess 11, is provided on each of the portions 6 and is disposed between adjacent pairs of the insulating sections 2. The web 10 and the recess 11 of each half portion 6 co-operate with the corresponding web 10 and recess 11 of the complementary half portion 6 to constitute a centrally apertured transverse seat for the ends of adjacent insulating sections 2 and a support for electrostatic-stress assuming members 12 and 14.

The complementary half portion 6 of the conducting sections 3 further comprise horizontal plate-like portions 16 constituting radial arms having laterally projecting portions 17 and apertures 18 therein.

The condensers 4 are each provided with apertured laterally-projecting lugs 19 that are disposed over the openings 18 in the arms 16 for the reception of bolts 20 by which the condensers 4 are secured in position. Radial flanges 21, on the under sides of the arms 16, serve to reinforce the latter.

The condensers 4 of each section 3 are electrically connected to each other by the portions 6 and the lugs 19 that constitute the low-potential terminals of the condensers.

High-potential terminals 23 of the condensers 4 of each section may be connected to the low potential terminals 19 of the condensers 4 next above by conductors 24 to thereby, connect all of the condensers 4 in multiple series relation. This construction causes the structure to constitute a unitary high-voltage condenser structure in which the total voltage thereacross is so divided into lower potential zones as to require the insulating sections 2 to be only of sufficient size to withstand the subdivided voltage drop.

The stress-assuming members 14 are each preferably provided with a screw-threaded socket portion 26 which bears against the discoidal seat portions 10 and is adapted to receive a screw-threaded end portion 27 of the stress-assuming member 12 next above which extends through the openings 11.

Each member 12 is provided with a substantially spheroidal upper end or head portion 28 that is disposed within a lower end portion 29 of the member 14 next above. The portion 29 is preferably of hollow substantially spheroidal shape having its inner surface in uniform spaced relation to the surface of the head 28. This construction provides a uniform field in an arc-gap 30 between the portions 28 and 29. A nut 31 assists in securing the members 12 and 14 in position on the portions 10.

The radial length of any portion of the arc-gap 30 is the shortest distance between each ad-

10 adjacent pair of the conducting sections 3 so that when an excessive voltage is impressed across the structure, breakdown will occur only between the members 12 and 14 to conduct the discharge current to ground before stresses are imposed on the remainder of the structure and exterior flash-over occurs. This function is materially assisted by the enclosure of the heads 28 in the portions 29 and 10 by the fact that all arcing distances outside the gaps 30 are greater than the latter.

15 In the form of my invention shown in Fig. 5, in which corresponding parts are designated by corresponding reference characters, the insulating sections 2, instead of being separate elements, are all intimately or integrally united. Such a structure may be formed of wood, fiber or any other suitable insulating material.

20 In this form, the clamping portions 9 are dispensed with and the complementary half portions 6 secured in position around an uncorrugated portion 33 of the integral sections 3, as by screws or bolts 34, that extend 25 through bushings 38 in the section 2. Also, the stress-assuming members 12 and 14 of each conducting section 3 are preferably integrally united to constitute one element or member having an apertured central portion 33 into which unthreaded ends 36 of the 30 screws 34 extend to hold the same in position. Cylindrical flexible insulating members 37 are disposed between the section 2 and the central portion 33 of the integral stress-assuming members 12 and 14.

25 By my invention, the central insulating column is relieved of all electrostatic stress effects and, by reason of the confined or enclosed relation of the safety gap 30, disruptive arcs are prevented from traveling beyond a definite local path between the conducting sections. The device is also safer in operation and adapted for service in connection with voltages of materially greater 35 values than other condensers of the same size.

30 While I have shown and described particular forms of my invention, changes may be effected therein without departing from the spirit and scope thereof, as set forth in the appended claims.

I claim as my invention:

1. An electrical structure built up to constitute a supporting rack or standard and comprising a plurality of alternate insulating and conducting sections, condensers supported by said conducting sections, and means providing a definite ultimate electrostatic breakdown path between the conducting sections.

2. An electrical structure built up to constitute a supporting rack or standard and comprising a plurality of alternate insulating and conducting sections, condensers supported by said conducting sections, and means providing a single ultimate electrostatic

flash-over path at a predetermined position between the conducting sections.

3. An electrical structure built up to constitute a supporting rack or standard and comprising a plurality of alternate insulating and conducting sections, condensers supported by said conducting sections, and means providing a single ultimate electrostatic flash-over path at a predetermined position within the structure.

4. An electrical structure built up to constitute a supporting rack or standard and comprising a plurality of alternate insulating and conducting sections, condensers supported by said conducting sections, and means providing a single ultimate electrostatic flash-over path at a predetermined position within the insulating sections.

5. An electrical structure built up to constitute a supporting rack or standard and comprising a plurality of alternate insulating and conducting sections, condensers supported by said conducting sections, and means for substantially entirely relieving the insulating sections of electrostatic stresses between the conducting sections.

6. An electrical structure built up to constitute a supporting rack or standard and comprising a plurality of alternate insulating and conducting sections, condensers supported by said conducting sections, and means for precluding the imposition on the insulating sections of damaging stresses in the electrostatic field between the conducting sections.

7. An electrical structure built up to constitute a supporting rack or standard and comprising a plurality of alternate insulating and conducting sections, condensers supported by said conducting sections, and means providing an enclosed ultimate arc-over path between the conducting sections.

8. An electrical structure built up to constitute a supporting rack or standard and comprising a plurality of alternate insulating and conducting sections, condensers supported by said conducting sections, including a hollow-insulating section, and means in said hollow-section for assuming an ultimate arc between the conducting sections adjacent thereto.

9. An electrical structure built up to constitute a supporting rack or standard and comprising a plurality of alternate insulating and conducting sections including a hollow insulating section, condensers supported by the conducting sections, and means in said hollow section for assuming an ultimate arc between the conducting sections adjacent thereto.

10. An electrical structure built up to constitute a supporting rack or standard and comprising a plurality of alternate insulating and conducting sections including a hollow insulating section, condensers supported by the conducting sections, and means in said

- hollow section for attracting all damaging electrostatic stresses between the adjacent conducting sections away from the remainder of the structure.
11. An electrical structure built up to constitute a supporting rack or standard and comprising a central column embodying alternate longitudinal insulating sections and laterally-projecting conducting sections, condensers supported by the conducting sections, said column being hollow between two adjacent conducting sections and means for directing the ultimate arc-over in an electrostatic field between said adjacent sections along a path in said hollow column portion. 70
12. An electrical structure built up to constitute a supporting rack or standard and comprising a central column embodying alternate longitudinal insulating sections and laterally-projecting conducting sections, condensers supported by the conducting sections, said column being hollow between two adjacent conducting sections and co-operating electrostatic-stress-assuming members disposed in said hollow portion and connected to said adjacent conducting sections. 75
13. An electrical structure built up to constitute a supporting rack or standard and comprising a central column embodying alternate longitudinal insulating sections and laterally-projecting conducting sections, condensers supported by the conducting sections, said column being hollow between two adjacent conducting sections, and an electrostatic stress-assuming member connected to each of said adjacent conducting sections and projecting toward the other stress-assuming member in said hollow portion. 80
14. An electrical structure built up to constitute a supporting rack or standard and comprising a central column embodying alternate longitudinal insulating sections and laterally-projecting conducting sections, condensers supported by the conducting sections, said column being hollow between two adjacent conducting sections, and an electrostatic-stress-assuming member connected to each of said adjacent conducting sections and projecting toward the other stress-assuming member in said hollow portion, the adjacent ends of said stress-assuming members being disposed in longitudinally overlapping spaced relation. 85
15. An electrical structure built up to constitute a supporting rack or standard and comprising a central column embodying alternate longitudinal insulating sections and laterally-projecting conducting sections, condensers supported by the conducting sections, said column being hollow between two adjacent conducting sections, and an electrostatic-stress-assuming member connected to each of said adjacent conducting sections and projecting toward the other stress-assuming member in said hollow portion, the adjacent ends of said stress-assuming members having surfaces shaped to uniformly distribute the electrostatic field therebetween. 90
16. An electrical structure built up to constitute a supporting rack or standard and comprising a central column embodying alternate longitudinal insulating sections and laterally-projecting conducting sections, condensers supported by the conducting sections, said column being hollow between two adjacent conducting sections, and an electrostatic-stress-assuming member connected to each of said adjacent conducting sections and projecting toward the other stress-assuming member in said hollow portion, the adjacent ends of said stress-assuming members being of substantially spheroidal shape. 95
17. An electrical structure built up to constitute a supporting rack or standard and comprising a central column embodying alternate longitudinal insulating sections and laterally-projecting conducting sections, condensers supported by the conducting sections, said column being hollow between two adjacent conducting sections, and an electrostatic-stress-assuming member connected to each of said adjacent conducting sections and projecting toward the other stress-assuming member in said hollow portion, one of said stress-assuming members having a curved exterior end surface and the other stress-assuming member being hollow and having a curved inner surface surrounding said hollow surface in uniform spaced relation thereto. 100
18. An electrical structure built up to constitute a supporting rack or standard and comprising a central column embodying alternate longitudinal insulating sections and laterally-projecting conducting sections, condensers supported by the conducting sections, said column being hollow between two adjacent conducting sections, and an electrostatic-stress-assuming member connected to each of said adjacent conducting sections and projecting toward the other stress-assuming member in said hollow portion, one of said stress-assuming members having a hollow end portion surrounding an end of the other stress-assuming member in spaced relation thereto. 105
19. An electrical structure comprising spaced conducting sections, condensers supported by the sections, an electrostatic-stress-assuming member connected to one of said conducting sections and projecting toward another thereof, and a second electrostatic-stress-assuming member connected to said other conducting section and projecting toward said first-stress-assuming member, an end of one of said stress-assuming members being enclosed by a portion of the other in spaced relation to said portion. 110
20. An electrical structure comprising spaced conducting sections, condensers supported by the sections, an electrostatic-stress-assuming member connected to one of said conducting sections and projecting toward another thereof, and a second electrostatic-stress-assuming member connected to said other conducting section and projecting toward said first-stress-assuming member, an end of one of said stress-assuming members being enclosed by a portion of the other in spaced relation to said portion. 115
21. An electrical structure comprising spaced conducting sections, condensers supported by the sections, an electrostatic-stress-assuming member connected to one of said conducting sections and projecting toward another thereof, and a second electrostatic-stress-assuming member connected to said other conducting section and projecting toward said first-stress-assuming member, an end of one of said stress-assuming members being enclosed by a portion of the other in spaced relation to said portion. 120
22. An electrical structure comprising spaced conducting sections, condensers supported by the sections, an electrostatic-stress-assuming member connected to one of said conducting sections and projecting toward another thereof, and a second electrostatic-stress-assuming member connected to said other conducting section and projecting toward said first-stress-assuming member, an end of one of said stress-assuming members being enclosed by a portion of the other in spaced relation to said portion. 125
23. An electrical structure comprising spaced conducting sections, condensers supported by the sections, an electrostatic-stress-assuming member connected to one of said conducting sections and projecting toward another thereof, and a second electrostatic-stress-assuming member connected to said other conducting section and projecting toward said first-stress-assuming member, an end of one of said stress-assuming members being enclosed by a portion of the other in spaced relation to said portion. 130

20. An electrical structure comprising spaced conducting sections, condensers supported by the sections, an electrostatic-stress-assuming member connected to one of said conducting sections and projecting toward another thereof, a second electrostatic-stress-assuming-member connected to said other conducting section and projecting toward said first stress-assuming member, an end of one of said stress-assuming members, being enclosed by a portion of the other in spaced relation to said portion, and means for enclosing said stress-assuming members. for providing an electrostatic break-down path, which means is common to the condensers connected in series and the condensers connected in parallel.

21. An electrical structure constituting a supporting rack or standard for electrical devices and comprising a hollow central insulating column portion and conducting portions of different potential in longitudinally spaced relation thereto, condensers supported by said conducting portions, and means for confining ultimate electrostatic flash-over, from one conducting portion to another, to a path within said hollow column portion.
22. An electrical structure constituting a supporting rack or standard for electrical devices and comprising a hollow central insulating column portion and conducting portions of different potential in longitudinally spaced relation thereto, condensers supported by said conducting portions, and means for confining ultimate electrostatic flash-over, from one conducting portion to another, to a path within said hollow column portion and preventing the imposition of damaging stresses on said portion.
23. An electrical structure in the form of a column, carrying a number of superposed conducting sections supporting condensers, and means providing an enclosed ultimate arc-over path between the conducting sections, and between the groups of condensers supported by any two adjacent conducting sections.
24. An electrical structure in the form of a column, carrying a number of superposed conducting sections supporting condensers, and means providing an enclosed ultimate arc-over path between the conducting sections and between the groups of condensers supported by any two adjacent conducting sections, said column having horizontal corrugations on its exterior.
25. An electrical structure built up to constitute a supporting rack and comprising a plurality of alternate insulating and conducting sections, condensers associated with the conducting sections and electrically connected thereto, and means for providing an electrostatic break-down path between adjacent conducting sections.
26. An electrical capacitative unit comprising a plurality of condensers connected in series parallel relation, means for supporting the condensers in fixed relation, and means
